UNITED STATES PATENT OFFICE.

LEWIS HALLOCK NASH, OF SOUTH NORWALK, CONNECTICUT, ASSIGNOR TO NASH
ENGINEERING COMPANY, OF NEW YORK, N. Y., A CORPORATION OF NEW YORK.

TURBO-DISPLACEMENT ENGINE.

1,045,732.

Specification of Letters Patent. Patented Nov. 26, 1912.

Application filed March 5, 1910. Serial No. 547,422.

To all whom it may concern:

Be it known that I, LEWIS HALLOCK NASH, engineer, a citizen of the United States of America, and a resident of South Norwalk, county of Fairfield, and State of Connecticut, have invented certain new and useful Improvements in Turbo-Displacement Engines, of which the following is a specification, illustrated by the accompanying drawings.

My invention is directed to improvements in motive power and consists in certain novel features of construction and operation, by which an elastic fluid, as steam or compressed air, is caused to give motive power to a device.

I have shown in the drawings various forms of structures embodying my invention and in order that persons skilled in the art may be able to practise my invention, the features which constitute my improvement will be described in the following specification and particularly pointed out in the claims.

In its principle of operation my invention partakes of the nature of an impact or turbine engine and also of a displacement structure and I have therefore called my device a turbo-displacement engine.

I will now describe the drawings which show several forms of structures having my improvement, in which:

Figure 1 represents a longitudinal section of a device having my invention. Fig. 2 is a section on the line 2, 2 of Fig. 1, looking in the direction of the arrow. Fig. 3 is a section on the line 3, 3 of Fig. 1, looking in the opposite direction. Fig. 4 is a view similar to Fig. 2, with the rotating propeller in place, showing the operation of the device. Fig. 5 is a view of the rotor. Fig. 6 is a modified form of case chamber. Figs. 7, 8, 9, 10 and 11 are views of another modification.

Referring to Figs. 1 to 4.—A is a case chamber, having passages *a* in its circumference and having an interior cylinder *b*. This interior cylinder has ports *c*, *c* opening communication between the interior and exterior portions of the case and also jet orifices *d*.

B is one of the cylinder heads, which is provided with an outlet passage *e* and ports

f leading thereto, shown in Fig. 2. The opposite end of the cylinder is provided with a head *C* which has an inlet passage *g*, and is provided with two ports *h*, *h* leading into the interior of the chamber.

Referring to Figs. 4 and 5: It will be seen that the wheel *D* is of cylindrical form, divided into interior chambers by blades *d'* which form division walls separating it into interior chambers. Each chamber is supplied with guide blades *d''* and ports *d'''* in each end of the chamber communicate at the proper time with the head ports previously referred to. In operation, the case chamber is filled with a liquid *E* which acts as a motive fluid. The rotor *D* is mounted on a shaft *F* and the sides of the rotor make joint forming contact with the heads of the closure.

Referring to Fig. 4: Assuming that the device is in rotation and that air or steam under pressure is admitted into the structure through the pipe *g* and the ports *h*, *h*, the pressure of the steam or compressed air will force the water out of the chambers *i*, *i* into the exterior passage *a* through the ports *a'*. This water will be driven under pressure to the orifices *a''* in the case walls, and the water will shoot in as a jet, strike in upon the blades *d''* in the chambers *k*, *k*, driving the wheel in the direction of the arrow. It will thus be seen that the chambers *i*, *i* are discharging and that the chambers *k*, *k* are receiving the liquid, while the chambers *m*, *m* are empty and the chambers *l*, *l* are filled.

The cycle of operations is as follows:— Supposing a chamber as *l*, in the position as shown in Fig. 4, the inlet ports *h*, *h* are just about in the position to open communication through the ports *d'''* of the rotor which communicate with the chambers *l*, *l* and the pressure of the steam or air will begin to drive the liquid out of the chamber *l* into the surrounding passage *a* and also by its continued pressure the liquid will be driven through the jet orifices *d* into the chambers *k*, *k*, and this effect will increase as the wheel advances farther into the position shown at *i*, *i*, when, the port being full open, the entire flow will be passing out of the chambers which are in the position *i*, *i*.

The chambers m , m are passing across the dividing position and are about to open communication with the outlet port and as they advance into the position of k , k this port is 5 fully opened, allowing the waste gases to escape into the discharge passage e of the engine. It will thus be seen that the rotor receives two impulses on each side, one the reaction due to the escape of the liquid from 10 the blades d^2 , and the other the impact of the liquid issuing through the orifices d , and this effect continues constantly during the revolution of the wheel. It will also be noticed that the wheel is double-acting and 15 that the liquid is escaping from opposite sides of the wheel, which tends to form a balance and prevents strain upon the shaft bearing. The water in the device is therefore transferred from a chamber under pressure 20 through orifices or passages formed by the case and caused to reenter another chamber, during which operation it exerts force as upon a turbine structure to produce power, while the gases are expanded in a 25 closure, one wall of which consists of a liquid piston and which liquid piston is driven out by the pressure of said gas. The driving effect, however, is due to the impact of the liquid upon the turbine structure and 30 the operation of the engine is therefore what I have termed a turbo-displacement engine. The centrifugal force of the revolving liquid causes it to take a position substantially concentric to the rotation of the wheel and 35 thereby separates the heavier from the lighter fluid.

Referring now to Fig. 6, it will be seen that a similar structure is shown, in which the passages are subdivided so that there are 40 two passages on each side of the engine. The operation of this form of device differs slightly from that already described in that the first passage, as for instance, a^s , a^s , receives the escaping liquid from the wheel 45 under the highest pressure as it escapes from the chambers d^s , d^s , and this liquid passing through the passage a^s , enters the wheel again in the chamber d^s which is open to the exhaust. When the chamber reaches the position d^s , d^s the liquid is expelled through 50 the passages a^s , a^s and enters into the chambers d^s , d^s , and the effect of this division of the chambers is that the gases can be expanded under a lower pressure in the chambers d^s , and a greater amount of power can 55 be recovered than in the form previously described. It will readily be seen that the plurality of passages could be increased until the degree of expansion is whatever is desired. The operation of the device will be 60 readily understood from the description of Figs. 1 to 5, with the differences stated.

It will thus be seen that in my improved engine I make use of a liquid as a means of 65 transmitting the power from a motive fluid

to a moving liquid and then take the force of the moving liquid upon a turbine structure to develop power. In the figures previously described the case passages have been formed exterior to the wheel chamber, but I 70 may form a passage between the periphery of the wheel and the case chamber of such size and dimensions as to cause a jet action in a similar way, and Figs. 7, 8, 9, 10 and 11 show views of such modified structure.

Referring now to Figs. 7, 8, 9, 10 and 11, it will be seen that the case chamber shown in Fig. 7 is a section taken upon the line 7, 7 of Fig. 8.

Fig. 10 shows an end view of the rotor; 80 and Fig. 11 shows a section through the center and illustrates the shape of the reaction blade and the entrance and discharge ports.

In Fig. 9 the case chamber is shown with the wheel removed so that the inlet and outlet ports are readily understood.

The case 6 is provided with the supply passage 7 and the discharge passage 8. The case 6 is closed upon the end with the cylinder heads 9, 9 which are provided with 90 the inlet ports 10, 10 and the outlet ports 11, 11. These ports are connected with the passages 7 and 8 in the case. The passages in the heads are preferably formed to open upward, in order that the liquid that may 95 flow into them can fall within the lower part and flood the ports 10 and 11 to keep the case chamber filled with liquid to the desired point. To prevent the liquid from escaping with the exhaust, the receiving 100 chamber 16 is constructed in the outlet passage into which the exhaust from the ports may whirl about and discharge the liquid before the gaseous portions pass out of the exhaust pipe.

The wheel 12 is mounted on the shaft 13 and operated in bearings so as to make a joint with one side of the case, while upon the other side a space is left between the wheel and the case which forms a jet passage for the water. The wheel is provided with arms 14 which are curved at their outer ends so as to form reaction surfaces to receive the impact of the liquid. The center of the wheel is provided with passages 15 110 which, acting with the ports 10, control the inflow of the fluid to the spaces on one side of the wheel, while upon the other side they 115 coact with the ports 11, 11 to control the exhaust of the working fluid.

Fig. 8 shows the wheel and the case in one position of its operation in order to show the action of the parts. It will be seen that the port 10 (shown in dotted lines) is in communication with the passages leading to the wheel spaces y , z , and o , while the exhaust port 11 is in communication with the wheel spaces s , t , u , v and w .

Suppose now that the wheel is revolving in the direction of the large arrow and that 130

the case chamber is filled with water to the level of the line *n*. The steam would be admitted through the port 10 to the space *z*, while the steam in the spaces *p*, *q* and *r* will be expanding. At the same time the spaces *s*, *t*, *u*, *v* and *w* will be in communication with the exhaust port 11, from which the steam can escape into the outlet pipe. The steam will therefore drive the water out from the spaces *z*, *o*, *p*, *q* and *r*, as shown by the arrows, and this water will flow through the passage formed between the wheel and its chamber in the direction indicated by the larger arrow, at a velocity greater than that of the wheel, and the water will enter these spaces by striking against the curved blades of the wheel and by its inertia exert a force in developing power. It will thus be seen that the effect in driving the rotor is, as before stated, due to the impact of the flowing liquid.

What I claim and desire to secure by Letters Patent of the United States is:—

1. In a turbo-displacement engine, the combination of a rotary member provided with chambers or spaces having entrance and discharge passages forming turbine structures, a case having passages leading from one of the chambers in the rotary member to another, a liquid passing out of one chamber in the rotary member into another therein combined with means for introducing a fluid under pressure to the chambers of said member for the purpose of driving said liquid.

2. A rotor for a turbo-displacement engine, consisting of a wheel divided by partitions into separate chambers, combined with tangential orifices of smaller area than said chambers formed in the walls of said wheel for receiving and ejecting a liquid, and ports near the center of said wheel for receiving and discharging a fluid.

3. In a turbo-displacement engine, the combination of a rotary turbine structure formed with chambers, one wall of said chambers being formed by a liquid, ports for introducing a lighter fluid into the center of said rotary turbine structure and ports for expelling the heavier liquid from said chambers, combined with a case having orifices for directing the liquid upon the rotary turbine structure.

4. The combination with a rotor having chambers, an inclosing case having passages in the walls thereof, a liquid entering and receding from said chambers, and means for directing the liquid through said passages upon the blades of said rotor.

5. A motor device consisting of a system of revolving chambers, a plurality of passages leading from one chamber to another, means for introducing a gaseous body into said chambers to expel the liquid and means for utilizing the force of the moving liquid in developing power.

6. A rotating body containing chambers, a case chamber having passages on opposite sides of said rotating body, said passages forming communication between one set of chambers and another set of chambers, a liquid revolving with said rotating body and flowing through said passages from one chamber to another, means for taking the power from the flowing liquid and means for introducing a gaseous body into the said chambers to drive said liquid.

7. A rotor consisting of a rotating member, divided into chambers, a series of curved blades forming passages guiding the liquid into and out of said chambers in tangential direction, means for introducing a fluid into said chambers to expel the liquid and a case chamber adapted to direct the flow of the liquid from one chamber to another.

8. The combination of a rotor containing chambers, with a case chamber having jet orifices discharging into one set of said rotor chambers and a passage in the case chamber leading to another set of said rotor chambers to receive liquid therefrom, and means for driving the liquid by the pressure of a lighter fluid.

9. A rotor piston, consisting of side and transverse walls forming chambers, ports in the side walls opening into said chambers, and transverse turbine blades arranged circumferentially of the rotor between said transverse walls.

10. A rotor piston consisting of side and transverse walls forming chambers, ports in the side walls opening into said chambers, and transverse turbine blades arranged circumferentially of the rotor between said transverse walls, said turbine blades terminating at their inner edges short of the center of the rotor.

11. A rotor piston consisting of side and transverse walls forming chambers, ports opening into said chambers through the side walls thereof, and tangential orifices at the circumferential portions of said chambers between said transverse walls.

12. A rotor piston consisting of side and transverse walls forming chambers, ports opening into said chambers through the side walls thereof, and tangential orifices at the circumferential portions of said chambers between said transverse walls, said tangential orifices being of less area than the area of the chambers.

13. In a turbo-displacement engine, the combination of a case chamber having a cylindrical rotor chamber and a passage around said rotor chamber, a cylindrical rotor within said cylindrical chamber, consisting of side and transverse walls forming chambers, ports in the side walls opening into said chambers and tangential orifices at the circumferential portions of said cham-

bers between said transverse walls, the wall of the cylindrical rotor chamber having oppositely disposed inlet and outlet ports, a liquid within the case, and means for introducing a fluid under pressure into the orifices in the side walls of the rotor.

In testimony whereof I have hereunto

signed my name in the presence of two subscribing witnesses.

LEWIS HALLOCK NASH.

OSCAR ASCHER.

Correction in Letters Patent No. 1,045,732.

It is hereby certified that in Letters Patent No. 1,045,732, granted November 26, 1912, upon the application of Lewis Hallock Nash, of South Norwalk, Connecticut, for an improvement in "Turbo-Displacement Engines," an error appears in the printed specification requiring correction as follows: Page 1, line 80, for the reference-letter " a^2 " read d ; and that the proper correction has been made in the files and records of the Patent Office and are hereby made in the said Letters Patent.

Signed and sealed this 1st day of April, A. D., 1913.

[SEAL.]

C. C. BILLINGS,

Acting Commissioner of Patents.

Correction in Letters Patent No. 1,045,732.

It is hereby certified that in Letters Patent No. 1,045,732, granted November 26, 1912, upon the application of Lewis Hallock Nash, of South Norwalk, Connecticut, for an improvement in "Turbo-Displacement Engines," an error appears in the printed specification requiring correction as follows: Page 1, line 80, for the reference-letter "*a²*" read *d*; and that the proper correction has been made in the files and records of the Patent Office and are hereby made in the said Letters Patent.

Signed and sealed this 1st day of April, A. D., 1913.
